UNITED STATES PATENT OFFICE.

EDWIN CLAY PEEBLES, OF CINCINNATI, OHIO, ASSIGNOR TO CHARLES WALTON AND WILLIAM A. HINSCH, BOTH OF SAME PLACE.

EGG-CARRIER.

SPECIFICATION forming part of Letters Patent No. 355,659, dated January 4, 1887.

Application filed May 7, 1886. Serial No. 201,413. (No model.)

To all whom it may concern:

Be it known that I, EDWIN CLAY PEEBLES, a resident of Cincinnati, Hamilton county, Ohio, have invented certain new and useful Improvements in Egg-Carriers, of which the following is a specification.

The object of my invention is to provide a cheap, safe, and convenient means for packing and carrying eggs and other fragile objects. 10 In the accompanying drawings, forming part of this specification, Figure 1 is a top view of my improved egg-carrier laid open and nearly flat. Fig. 2 is a vertical longitudinal section of the carrier closed. Fig. 3 is a perspective view of part of the open carrier, showing the bottom, the two ends, and the partitions between the individual egg-spaces. Fig. 4 is a view of the form of cross-partition for use in a case especially adapted to carrying rosebuds. 20 Fig. 5 is an end view of the partitions. Fig. 6 shows the blank from which the box is made.

The device consists, essentially, of a box of peculiar structure containing partitions which divide it into spaces, each capable of holding 25 one egg or other small object. This box itself is preferably made of a single piece of pasteboard. This piece of pasteboard is folded along the dotted lines shown in Fig. 6, and cut through on the solid lines shown in the 30 same figure. This divides the piece of pasteboard into four main divisions, A, B, C, and D, of which A and C make the two sides of the box, and B and D the bottom and top, respectively. The parts a, b, c, and d close in the 35 ends of the box. The parts A, B, C, and D differ in length, A being the shortest, B slightly longer than C, and D the longest. After being cut and bent the pasteboard is folded into the shape of a box, the four end pieces at each 40 end being arranged in the order shown in Figs. 1 and 2. The difference in length of the parts A, B, C, and D admit of this folding. When in this position, an awl or similar tool is passed through each end, preferably near the top and 45 toward the median line, forming openings in each of the four end parts. These openings are marked, respectively, a', b', c', and d' in the drawings. The cord S is passed through the openings in the manner shown in Fig. 1. Com- 50 mencing at the opening d' of one end, it is passed in turn through each of the openings at

that end of the box, always passing from without inwardly. It is then passed over to the other end of the box, and is passed through each of the openings there, commencing with 55 the opening a', and always being passed from within outwardly.

The spaces in the box are formed by the partitions E and F. The partition E extends lengthwise of the box, through the center, and 60 is secured to the part B by two or more hinges, H, made of some flexible material, and pasted to the partition, and also to the bottom B. The longitudinal partition E is provided with vertical slots e, cut on the edge adjoining the box, 65 and which embrace the cross-partitions F, and the cross-partitions F are similarly provided with slots f, which embrace the longitudinal partition E, thereby preventing the cross-partitions F from being withdrawn when the partitions stand vertically. These slots are pref- 70 erably made wide, so that the cross-partitions may be folded flat against the longitudinal partition. The hinges H then allow the longitudinal partition to be laid flat on the bottom 75 B, thus saving space in packing the empty cases.

The number of egg-spaces in the case is immaterial to the invention, but for the purposes for which this case is intended twelve is a 80 convenient number.

The mode of operation is quite simple. The case is opened so as to expose the spaces, which are then filled. The cord S is then tightened, and in so doing it is drawn in a straight line, 85 which closes the box, and brings the openings in the ends into the same straight line in which they were originally made. The excess of cord is now used in tying up the box by being, pref- 90 erably, first drawn down and under the box.

The special advantage of this case is that by its use there need be but one handling of the egg from the nest to the consumer, no matter at what distance they may be apart, as the individual cases may be packed by the farmer 95 as he collects the eggs, and the cases then shipped in usual thirty-dozen lots of commerce, as they are put up at the farm. The separate cases may also be delivered by the grocer to the consumer without rehauling the eggs. 100

What I claim as new and of my invention, and desire to secure by Letters Patent, is—

1. The box consisting of the parts A, B, C, and D, end pieces, *a*, *b*, *c*, and *d*, provided with openings *a'*, *b'*, *c'*, and *d'*, and cord S, as and for the purposes specified.
- 5 2. The combination of the box consisting of a single piece of pasteboard or other suitable material folded into the parts A, B, C, and D, provided with the ends *a*, *b*, *c*, and *d*, having openings *a'*, *b'*, *c'*, and *d'*, cord S, and 10 partitions E and F, substantially as and for the purposes specified.
3. In an egg-carrier, the partitions E and F, provided with wide slots *e* and *f*, the partition E being hinged to the box, as and for the purposes set forth.

EDWIN CLAY PEEBLES.
